UNITED STATES PATENT OFFICE.

EDWARD R. SNYDER, OF EAST ORANGE, NEW JERSEY, AND CHARLES W. MORTIMER, OF BROOKLYN, NEW YORK, ASSIGNEES TO THE BARRETT COMPANY, A CORPORATION OF NEW JERSEY.

ROOF COVERING.

Application filed January 26, 1920. Serial No. 354,044.

To all whom it may concern:

Be it known that we, EDWARD R. SNYDER and CHARLES W. MORTIMER, citizens of the United States, residing at East Orange and Brooklyn, in the counties of Essex and Kings, and States of New Jersey and New York, have invented certain new and useful Improvements in Roof Coverings, of which the following is a specification.

10 This invention relates to the production of shingles and the process of laying the shingles.

Heretofore it has been customary to make flexible roofing material by making a felt base and saturating the same with waterproofing material, after which it was coated on one or both sides with plastic material and a layer of wear-resisting material such as crushed stone, slate, etc., was applied.

20 These sheets were cut into strips or shingles or multi-shingles and applied for covering roofs. One of the objections has been the monotonous appearance, and another objection has been that the corners of the shingles

25 would curl up, or be blown up by the wind.

The object of this invention is to provide a roof covering of flexible material which shall be pleasing in appearance and in which danger of curling or turning up at the ends or corners is minimized.

The invention will be understood from the description in connection with the accompanying drawing, in which—

Fig. 1 represents a plan view of the shingle.

Fig. 2 represents a plan view of a similar shingle with the corners cut away.

Fig. 3 represents a plan view of a similar shingle with the vertex cut off.

40 Fig. 4 represents a plan view of a similar shingle with the corners and the vertex cut off.

Fig. 5 represents a sheet of roofing material showing the lines along which it is cut

45 to produce the shingles of Fig. 3 or 4.

Fig. 6 shows a sheet of roofing material with the lines along which it may be cut to produce the shingles of Figs. 1 and 4.

50 Fig. 7 represents a group of shingles in the course of installation.

Fig. 8 represents a course of shingles as they appear on the roof.

Fig. 9 represents a course similar to Fig. 8, but made of other shingles.

Fig. 10 is a figure similar to Fig. 7 representing a modification.

Fig. 11 is a figure similar to Fig. 9 representing two overlapping rows of shingles.

Fig. 12 is a section through the shingle.

In practicing this invention, the shingles which should be made of flexible material may be cut from a sheet of roofing material having a wear-resisting layer 15 on one side thereof as more clearly shown in section in Fig. 12 so as to obtain shingles of the shape represented by reference character 1 in Fig. 1. Shingles of the shape represented by reference character 2 of Fig. 2 may be obtained by cutting the corners off along the lines 3—3 of Fig. 2. Shingles of the shape represented by reference character 4 of Fig. 4 may be obtained by cutting off the vertex along the line 5, as shown, and shingles of the shape represented by reference characters 6 of Fig. 4 may be obtained by cutting off the corners along the lines 7—7 and cutting off the vertex along the line 8.

It is obvious that the shingles in Fig. 1 may be cut from a strip of roofing material without involving any waste whatever by so cutting the strip that the bases of every other shingle are along one edge of the strip, and the bases of the other shingles are along the other edge. Shingles of the shape represented in Fig. 3 may be cut from a strip without waste in a similar way by merely having the lines c—c (Fig. 5) spaced further apart than would be the case if exact triangles were desired. Also by cutting the strip as represented at the right-hand end of Fig. 5 shingles of the shape shown in Fig. 4 can be produced with a waste of no material except the small triangles near the line 7—7 of Fig. 5.

Fig. 6 shows a lay-out by which shingles of the shape of Fig. 1 and those of the shape of Fig. 4 can be obtained from a single strip of roofing material without the waste of a particle of material. It is obvious that in this case the altitudes of the shingles 1' and 6' will differ from each other. These two types of shingles may be sold to different customers or may be used on different roofs or they may even be used together as represented in Fig. 9 on the same roof.

In installing the flexible shingles of the type described in this application, a row of the shingles will be laid side by side with

their bases substantially parallel with each other, and with their wear-resisting surface in contact with the roof deck as shown in Fig. 7. A nail or fastening means 9 may then be driven through the upper portion of the shingle 1 into the roof deck. A second row of shingles 1 is then laid in a similar manner except that the wear-resisting surface is turned up and the lower corners 10 of the shingles in the second row overlap the upper ends of the shingles of the first row. Nails or fastening means 10 may then be driven through the lower corners of the shingles of the second row and through the upper end of the shingles of the first row into the roof deck. The lower portions of the shingles of the first row are then turned upwards and laid over the spaces between the shingles of the second row and overlap 20 their edges as indicated in Fig. 8. It is to be noticed that the amount of lap between the lines 11 and 12 can be regulated by the distance that is maintained between the bases of the first and second rows as they 25 are being installed as shown in Fig. 7. A large portion of the points which project above the line 14 in Fig. 7 and the points that are turned under as shown in dotted lines in this figure is waste material so that 30 a portion of the same can be cut off as represented in Fig. 3 or the shingles can be so formed that this material is not wasted as shown in Fig. 5. The overlapping of a row of shingles over the edges of the row underneath them can also be regulated by cutting away the corners as indicated in Fig. 2. Fig. 9 shows clearly how the useless projection of the points shown in the upper portion of Fig. 8 can be obviated by cutting the 35 shingles as represented in Fig. 6.

With the various expedients by which the user can regulate the overlap of the shingles of one row upon those of another row, he can have a wide option as to the amount of 40 roofing material required per square of roof surface. The three thicknesses of material along a portion of the lower edge 13 (Fig. 8) or the four thicknesses along a portion of the lower edge (Fig. 10) of a course will 45 enhance the shadow effect and relieve the monotonous appearance. By alternating with shingles, surfaced with assorted colors of surfacing materials, the appearance may also be improved.

It will be understood that when a course of shingles has been installed by having one row overlapping another row, as represented in Figs 8 and 9, that the next course farther up the roof will be installed so that its lower edge 1' overlaps the upper edge 6' of the course previously installed as shown in Fig. 11.

Instead of installing the shingles as indicated in Fig. 7 with the lower corners of the shingles 1 of the upper row adjacent each

other, they may be made to overlap so that one nail would hold these corners and also the vertex of a shingle in the lower row as indicated at 14, Fig. 10. The danger of the lower corners of the shingles curling up 70 is eliminated with either installation.

The shingles may be formed so that the converging lines as shown in Figs. 3 and 4 will be very far apart, say two or three feet or more, so that the shingles become strips. 75 These strips could still be installed like the shingles 6' in Fig. 9 without departing from the invention. It is obvious that two or more variegated colors may be used if desired to give a more pleasing appearance to 80 the roof, or some of the shingles may be of one color and others of another.

We claim:

1. In the process of covering a roof, the steps which comprise laying a row of triangularly shaped pieces of roofing material side by side, with their bases parallel, laying a second row above said first row, and folding the lower part of said first row, over said 90 second row.

2. In the process of covering a roof, the steps which comprise laying a row of triangularly shaped pieces of roofing material side by side, with their bases parallel, laying a second row above said first row, with their 95 lower corners overlapping the upper portions of said first row, and folding the lower part of said first row over said second row.

3. In a roof, triangularly shaped shingles arranged in horizontal rows with two sets of said shingles in each row, one set being arranged with their bases extending in a downward direction and the other set being arranged with their bases extending in an upward direction, said last named set having the ends opposite their bases also extending in an upward direction. 105

4. In a roof, triangularly shaped shingles arranged in horizontal rows of underlying and overlapping shingles, the underlying shingles having their bases downward and the overlapping shingles having their bases upward, said overlapping shingles having their narrow ends extending upwardly. 110

5. In a roof, triangularly shaped shingles arranged in horizontal rows of underlying and overlapping shingles, the underlying shingles having their bases downward and the overlapping shingles having their bases upward, the vertices of the overlapping shingles being turned inwardly and upwardly. 115

6. In a roof, triangularly shaped shingles arranged in horizontal rows of underlying and overlapping shingles, the underlying shingles having their bases downward and the overlapping shingles having their bases upward, the vertices of the overlapping shingles being bent around the lower corners of the said underlying shingles. 120 125 130

7. In a roof, triangularly shaped shingles arranged in horizontal rows of underlying and overlapping shingles, the underlying shingles having their bases downward and the overlapping shingles having their bases and also their opposite ends extending upwardly.

8. In a roof, triangularly shaped shingles arranged in horizontal rows with two sets 10 of said shingles in each row, one set being arranged with their bases extending in a downward direction and the other set being arranged with their bases extending in an upward direction, and their other ends 15 underlying said first named set.

9. In the process of covering a roof, the steps which comprise laying a row of triangularly shaped pieces of roofing material side by side, with their bases parallel, laying 20 a second row above said first row, and folding the lower part of said first row, over said second row, said pieces of roofing material having wear resisting material on one side thereof, said first row being initially laid 25 with the wear resisting material inward and

the second row being laid with the wear resisting material outward.

10. The process which comprises laying a row of triangularly shaped pieces of roofing material, comprising a felt base and a coating 30 of wear-resisting material, with their bases parallel, laying a second row higher along the roof than said first row and folding the lower part of said first row over said second row.

11. The process which comprises laying a row of triangularly shaped pieces of roofing material, comprising a felt base and a coating 35 of wear-resisting material, with their bases parallel and the wear-resisting material beneath, laying a second row higher along the roof than said first row with the lower corners of their bases overlapping the upper ends of said first row and the wear-resisting material outwards, and folding the bases of 40 said first row over said second row.

In testimony whereof we affix our signatures.

EDWARD R. SNYDER.
CHARLES W. MORTIMER.
